SLUSH PUMP VALVE

Clarence White, Walnut Park, Calif., assignor to
Oil Well Manufacturing Corporation, Los
Angeles, Calif., a corporation of California

Application July 14, 1934, Serial No. 735,229

2 Claims. (Cl. 251—144)

My invention relates to valve structures, and more particularly to a novel form of slush pump valve structure.

In drilling oil wells by the rotary method, it is customary to continuously supply rotary mud under pressure to the rotating bit through the drill pipe. A slush pump is utilized for developing this high pressure. The valves of a slush pump ordinarily comprise a stationary seat with a pressure operated valve member adapted to seat thereon to form a fluid-tight fit when the pressure on one side of the valve becomes greater than on the other side thereof by a predetermined amount.

15 The mud used in ordinary drilling operations contains large quantities of abrasive matter, and quickly wears away the valve member and the seat member.

It is well known that a flexible rubber valve, 20 due to its ability to conform to a rough seat is the most satisfactory form of valve for slush pumps, disregarding pressure conditions. It is also well known that an all-metal valve, while capable of sustaining extreme pressures, quickly 25 wears and cuts away when subjected to use in pumping fluid containing abrasive matter.

One object of my invention is to provide a valve 30 structure which will sustain the extreme pressure loads developed in slush pumps and at the same time retain the ability of a flexible valve to conform to rough and uneven seats.

It is another object of my invention to provide a valve construction embodying a metal valve body adapted for engagement with a metal 35 valve seat for carrying the pressure load and in combination therewith a flexible sealing disc adapted to form a seal around the valve body when the body is seated.

It is another object of the invention to provide 40 a valve construction as described in the above paragraph in which the sealing disc engages the seat in such a manner as to provide an annular space between the valve and the disc when the valve is seated to receive any fluid 45 which may be forced upwardly between the valve and the seat as the valve is seated.

It is another object of my invention to provide 50 in a structure of the character described above a resilient clip means for removably attaching the flexible sealing disc to the valve body, there being no threaded parts which might become frozen during operation causing difficulty in disassembling the parts of the valve for replacement of the flexible disc.

55 These and other objects of my invention will

be better understood from a perusal of the following part of the specification and the appended claims, in connection with the accompanying drawing which is for illustrative purposes only.

In the drawing.

Fig. 1 is a utility view illustrating a slush pump equipped with the valve structures embodying the features of my invention.

Fig. 2 is a sectional view of one of the valve structures showing the valve in closed position.

Fig. 3 is a sectional view taken as indicated by the line 3—3 of Fig. 2.

Fig. 4 is a sectional view taken as indicated by the line 4—4 of Fig. 2.

Fig. 5 is a sectional view taken as indicated by the line 5—5 of Fig. 2, this view illustrating a novel resilient clip for retaining the parts of the valve together.

Fig. 6 is a detailed perspective view of the clip member shown in Fig. 5.

Referring to Fig. 1, I have illustrated a slush pump, generally designated by the numeral 10, having a prime mover 11 operatively connected by a connecting rod 12 to a pump section 13. The prime mover is such that the rod 12 is reciprocated, this rod carrying therewith a piston 15 slidable in a liner 16. This liner provides a cylinder 17 which is open at both ends so as to communicate with valve passages 18 and 19 formed in a housing 20 of the pump section 13. These valve passages conduct mud from an intake passage 21, this flow of mud being controlled by valve structures 30 closing valve seats provided in a valve deck 22 included in the housing 20, which valve structures incorporate the features of my invention.

In the type of slush pump shown, these valves are intermittently operated by a pressure differential which exists between the intake passage 21 and the valve passages 18 and 19 as the piston 15 is reciprocated. When the piston 15 is moved to the left from the position in which it is shown in Fig. 1, the right hand valve structure will be open, thus allowing mud to pass therethrough and through the valve passage 18, as indicated by the arrow 23, so that this mud fills the increasing volume of the cylinder 17 on the rightward side of the piston 15 as the piston moves leftward. The left hand valve structure 30 is at this time closed and the piston forces the mud in the left end of the cylinder 17 through a discharge structure 24. The valve structures 30 are identical and the details of these structures are illustrated in Figs. 2 to 6, inclusive.

Referring to Fig. 2, the valve deck 22 is provided

with an upwardly diverging tapered passage 32 adapted to receive a tapered metal valve seat 33, preferably in press fit relationship therewith. The valve seat 33 is provided with an upwardly 5 facing conical seating surface 34 and a central hub 35 providing an axial bore 36. The hub 35 is integrally connected to the body portion of the seat member 33 by a web 37 substantially in the manner shown, so as to provide a fluid passage 10 38 through the seat member.

Provided in the housing 20 directly above the valve structure 30 is an opening 40 of sufficient diameter to allow the passage of the valve structure 30 therethrough. The opening 40 is closed 15 by a suitable cap 41 having a central recess 42 adapted to receive a bushing 43 providing a bore 44 which extends co-axially with the bore 36 in the hub 35.

I provide a valve generally designated by the 20 numeral 50 which comprises a body 51 having a seating portion 52 conforming to the shape of the seating surface 34 of the seat 33, which body is designed to carry the pressure load on the valve. The valve body 51 is provided with a pin portion 25 53 which is preferably integral therewith and which projects axially on opposite sides of the valve body 51 so as to be slidably received in the bores 44 and 36 substantially in the manner shown for the purpose of guiding the valve body 30 51. The upper end 55 of the pin portion 53 is provided with a plurality of longitudinal grooves 56 so that the pin 55 may be freely slideable in the bore 44.

Carried by the body portion 51 is a centrally 35 apertured flexible disc 57 formed of rubber or other suitable flexible material. The disc 57 is preferably in the form of an annular ring which surrounds the pin 53 and rests upon the upper surface 58 of the valve body 51, this disc being 40 of larger diameter than the diameter of the body 51 so as to extend outwardly beyond the periphery thereof substantially in the manner indicated in Fig. 2.

Positioned on top of the disc 57 is a centrally 45 apertured pressure plate 60. Formed in the upper pin portion 55 adjacent the pressure plate 60 is a shoulder 62 which is formed preferably by providing an annular groove 63 in the outer surface of the pin 55. The shoulder 62 is provided 50 to serve as an abutment for a resilient clip 70 adapted to pressurally retain the above described parts together so that the lower surface of the disc 57 is maintained in close surface contact with the upper surface 58 of the valve body 51.

The clip 70 is formed of a plate having a central opening 72 of a diameter to receive the reduced diameter portion 73 formed in the upper pin 55 by the annular groove 63. The clip is provided with a pair of fingers 75 and 76 cooperating 60 to form a passage 77 through one side of the plate communicating with the central opening 72. As illustrated in Figs. 5 and 6, the width of one portion 78 of this passage is smaller than the diameter of the central opening 72. The outer 65 portions of the fingers 75 and 76 are preferably tapered outwardly and bevelled upwardly substantially in the manner shown at 80 in Figs. 5 and 6. Formed in the clip 70 on the opposite side from the passage 77 is a cut-out portion 81 communicating with the opening 72 in such a 70 manner that the walls formed by the opening 72 provide a pair of arcuate segments spaced as shown from the integral resilient portion joining the fingers 75 and 76.

With the disc 57 and the pressure plate 60

assembled on the valve body 51 as shown and previously described, the clip 70 is positioned on the pressure plate 60 so that the tapered surfaces 80 of the fingers 75 and 76 engage the lower surface of the shoulder 62. The clip 70 is then driven or otherwise forced laterally so that the fingers 75 and 76 snap around the reduced diameter portion 73 into the position shown in Fig. 5, which serves to confine the flexible disc 57 between the clip 70 and the body 51. It is obvious 10 that for removal of the disc 57 from the valve body it is only necessary to force the clip 70 in the opposite direction to that above described, whereupon the pressure plate 60 and the disc 57 may be removed from the valve for replacement 15 or for the purpose of turning the valve disc 57 over.

I prefer to utilize a means of centralizing the flexible disc 57 with relation to the valve, which means comprises an upwardly extending annular 20 rib 90 formed on the upper surface 58 of the valve body 51, which rib is adapted to extend into one of a pair of annular grooves 92 formed on opposite faces of the disc 57 substantially as shown in Fig. 2.

It is, of course, obvious that the central aperture of the disc 57 with relation to the diameter of the upper pin portion 55 may be such as to serve as a centralizing means for the disc, if preferred.

Confined between the pressure plate 60 and a suitable surface provided on the cap 41 or the bushing 43 is a compression spring 95 adapted to constantly urge the valve body into engagement with the seat 33.

In the operation of the valve, the valve body 51 seating on the surface 34 of the seat 33 carries the pressure load on the valve, and the portion of the disc 57 extending outwardly beyond the periphery of the body 51 engages the surface of 40 the seat around the periphery of the body 51, forming a seal therearound, the pressure in the valve passage above the valve deck forcing the flexible disc into intimate contact with the upper surface of the seat.

It will be noted in Fig. 2 that the respective diameters of the disc 57 and the valve body 51 with relation to the depth of the conical seating surface 34 is such that the disc, the valve and the upper portion of the surface 34 cooperate to provide an annular space surrounding the valve when it is seated. This is an important feature of the invention, the purpose of this space 100 being to receive any fluid which might be forced upwardly between the valve 51 and the seating surface 34 when the valve is seated. Thus none of the fluid which might contain relatively large bodies of abrasive matter is forced outwardly between the disc 57 and the upper surface of the seat after the disc is seated, obviating the likelihood of any of these bodies of matter becoming lodged between the disc and the seat and destroying the sealing efficiency of the disc.

It is, of course, obvious that in installations where removable insert valve seats are not used, and the valve seat is formed in the valve deck 22, the disc 57 is adapted to engage the upper surface of the deck 22 in substantially the same manner as described in connection with the valve seat 33.

Although I have herein described only one complete embodiment of my invention, it should be understood that various changes might be made, and other embodiments of the structure devised without departing from the scope of the

invention, which should be interpreted by the appended claims.

I claim as my invention:

1. In a valve structure, the combination of: 5 a valve body adapted to engage a seat and including a pin portion; a flexible disc carried by said body and having a seating face on each side thereof, said disc being reversible to dispose either of said seating faces for engagement with said seat when said valve body is seated to form a seal therearound; walls forming an annular groove in opposite faces of said disc; an annular rib formed on said body and extending into one of said grooves for centralizing said disc on said body; a 10 pressure plate on said pin for retaining said disc; a shoulder formed on said pin adjacent said plate; and a clip engaging said shoulder for retaining said plate, said clip comprising a pair of relatively spaced fingers integrally joined by a resilient portion, each of said fingers having an inwardly extending arcuate segment spaced from said resilient portion and adapted to fit said pin and the inner sides of the free ends of said fingers being tapered outwardly and beveled upwardly so that the space between said fingers is narrowest adjacent said segments, said beveled portions engaging said shoulder on said pin to increasingly press said plate against said disc when said clip is forced laterally between said shoulder and said

plate, said resilient portion allowing said fingers to spread to allow said arcuate segments to snap around said pin in grasping relation, and said tapered portions being adapted to guide said clip into engaging position.

2. In a valve structure, the combination of: a 5 valve body adapted to engage a seat and including a pin portion; a flexible disc carried by said body and having a seating face on either side thereof, said disc being reversible to dispose 10 either of said seating faces for engagement with said seat when said valve body is seated to form a seal therearound; walls forming an annular groove in opposite faces of said disc; an annular rib formed on said body and extending into one of 15 said grooves for centralizing said disc on said body; a pressure plate on said pin for retaining said disc; a shoulder formed on said pin adjacent said plate; and a laterally movable retaining clip including resiliently connected fingers providing 20 grasping segments adapted to snap around said pin into engagement with said shoulder, beveled surfaces on said fingers adapted to compress said disc against said valve body when said clip is forced laterally and tapered portions on said fingers adapted to guide said clip into engagement 25 with said shoulder.

CLARENCE WHITE.
